UNITED STATES PATENT OFFICE.

CECIL L. WATERMAN, OF MILFORD, IOWA.

MOLD FOR FORMING POURED BRICKS OR BLOCKS.

1,182,122.

Specification of Letters Patent.

Patented May 9, 1916.

Application filed July 14, 1915. Serial No. 39,868.

To all whom it may concern:

Be it known that I, CECIL L. WATERMAN, a citizen of the United States, residing at Milford, in the county of Dickinson and State of Iowa, have invented certain new and useful Improvements in Molds for Forming Poured Bricks or Blocks, of which the following is a specification, reference being had to the accompanying drawings.

10 My invention relates to devices for molding plastic materials, and particularly to devices for molding bricks or blocks to be used in building construction.

One object of my invention is the provision of a very simple, easily handled, easily set up mold whereby bricks or blocks of concrete or other plastic material may be readily molded, the mold being so constructed that it may be readily taken apart 20 when necessary and so formed that bricks or blocks of different sizes may be molded by the same apparatus.

A further object of the invention is the provision of a mold so constructed that 25 either an ornamental or a plain face may be given to the brick or block.

Still another object of the invention is to so construct the mold that, if desired, binding bricks or blocks may be molded therein.

30 Other objects will appear in the course of the following description.

My invention is illustrated in the accompanying drawings, wherein:

Figure 1 is a plan view of my improved 35 mold; Fig. 2 is an end elevation partly broken away; Fig. 3 is a fragmentary top plan view of another arrangement of the mold partitions; Fig. 4 is a like view to Fig. 3, but showing still another arrangement of the mold partitions; Fig. 5 is a fragmentary 40 longitudinal section of the mold; Fig. 6 is a perspective detailed view of the binding brick formed upon the pallet 18; Fig. 7 is a perspective detailed view of the pallets 45 16; Fig. 8 is a perspective detailed view of one of the side walls 14; Fig. 9 is a perspective detailed view showing the manner in which the partition plates engage with the middle wall.

50 Referring to the drawings, 2 designates the base of the mold which may be made of any suitable material and has a flat upper face and is supported by the longitudinally extending beams 3. Extending longitudi-

nally with the member 3 is the wall 4 which 55 is fixedly mounted upon the base 2 in any suitable manner, as by the U-shaped strip 5 which extends over one end of the partition wall and is held to the base 2 by means of screws. At its opposite end the partition 60 wall 4 is supported by means of a bracket 6 U-shaped in plan and having ears 7 whereby it is attached to the base 2. As before remarked, this partition wall 4 is held rigidly to the base but may be removed by lifting up 65 that end of the partition wall 4 engaged with the bracket 6 and then slipping the partition wall out from under the strip 5. Thus while the partition wall 4 is easily supported upon the base in relation to the side walls 70 8 and 9, it may, however, be removed from the base entirely. Coacting with the partition wall 4 are a pair of movable side walls 8 and 9. These walls of course extend parallel to the wall 4, and the walls are held in 75 this parallel relation and firmly connected to the base 2 by means of the angular brackets 10. These brackets simply bear against the walls and have outwardly extending bases which are slotted as at 11 for 80 the passage of bolts or screws so that they may be rigidly clamped in place.

The inner face of the wall 8 is formed with notches 11^a spaced a predetermined distance apart, and the confronting face of the 85 wall 4 is also formed with notches 12 spaced the same distance apart as are the notches 11^a. The inner face of the wall 9 is also formed with notches 11^a, and like the wall 8 these notches are formed upon the confronting face of the wall 4. These notches are adapted to receive the transversely extending partition plates 13 or 14, these partition plates holding the walls 8 and 9 spaced from the wall 4. Preferably, both faces of the 90 wall 4 between the notches are lined with removable plates of metal, designated 15, these plates being of such size that they will not cover the notches 12. The inner faces of the walls 8 and 9 are also provided with these 100 plates 15, except as will be hereafter stated. By reason of the fact that the partition wall 4 is removable it is possible to remove one partition wall and substitute another therefor having notches 12 which are nearer together or farther apart than the notches in the removed partition wall, the corresponding side walls 8 and 9 being also removed 105

and other side walls used having notches 11^a nearer together or farther apart.

For the purpose of supporting the molded mass of semi-plastic material within the mold spaces defined by the vertical walls, I provide the pallets 16, 17 and 18. These pallets are all the same except that they are of different size, and each pallet has preferably a smooth upper face and has depending 10 feet or lugs 19 formed upon its under face supporting the under face of the pallet about three quarters of an inch above the base 2. It will be seen that as the lining plates 15 extend the full depth of the mold spaces and that as the pallets are supported above the base 2, these pallets will act to hold the lining plates in place by bearing against the lining plates above their lower edges.

Attached to one end of the base 2 is a rail 20 extending exactly at right angles to the partition wall 4 and against which the walls 8 and 9 may be abutted so as to bring these walls into such a position that the notches 11^a in these walls will be exactly opposite the notches 12 in the wall 4.

The wall 8 and the wall 4 in addition to the notches 11 and 12 are likewise provided adjacent one end with the notches 21 for the purpose which will now be described.

It is often desirable to mold a binding brick of the form shown in Fig. 6. This brick, as will be seen from Fig. 6, is angular in form. The brick is ten inches long and the bottom of the main portion of the brick is ten inches wide. At one end the brick 22 is recessed, as at 23, and is laterally extended as at 24. The distance between the wall of the recess 23 and the end wall of the portion 24 is eight inches. Thus this binding or tie brick is in plan view as if two bricks had been laid together with the side edge of one brick abutting against the end edge of another brick and the first-named brick offset with relation to the second-named brick. By this construction the tie brick when laid up in the wall, looks exactly the same in effect as the other brick but extends inward across the space between the inner and outer walls and the portion in the inner end takes its place in the bricks of the inner wall and has exactly the same form as these bricks. For the purpose of molding these tie bricks, I provide the pallet 50 18, previously referred to, which is twelve inches in length and eight inches wide. One of the partitions 13 is moved down to the end notch 21 in order to accommodate this pallet and the oppositely disposed plates 25. These plates are twelve inches long by two and one-half inches high. They are made of sheet brass or sheet iron, or preferably of iron, and they may either be fastened rigidly to the form rails or walls 9 and 4 or 60 left loose, as circumstances may direct.

Cores 26 may be disposed upon the pallet to provide for the angular formation of the tie brick.

It will be seen that with the construction illustrated full sized bricks may be formed 70 between the walls 4 and 9, these bricks being four inches wide, two inches thick, and eight inches long, that is, of standard size, and, as illustrated in Fig. 2, between the wall 4 and the wall 9, bricks half this size 75 may be made. If, however, it is desired to form full sized bricks on both sides of the wall 4, the wall 9 may be shifted outward and engaged with screws or bolts 27, and in that case the partition walls 14 may be used 80 between the walls 4 and 8 in the same manner that the partition walls 13 are shown as being used (see Fig. 3). There is no difference between the walls 13 and 14, except in size. The wall 8 is likewise adjustable 85 with relation to the wall 4 so that only half sized bricks or blocks may be made, as in Fig. 4, if desired. It will thus be seen that my mold is adapted to form either full sized 90 bricks, half sized bricks, or tie bricks.

The partition plates 14 and the partition plates 13 may be either plain or so formed as to give an ornamental contour to the brick. Thus, as illustrated in Fig. 8, the partition plate 14 (and the same applies to the partition plate 13) is shown as being 95 of such length that it may be inserted in the grooves in the walls 4 and 9 or 4 and 8. Inward of the margin of the plate there is an outwardly beveled portion 14^a bounding a smooth central portion 14^b. By the use of plates of this character, I can form the bricks with beveled faces. The plates 15 may also be formed with these beveled 100 faces, or have some other ornamental configuration so as to simulate ashler or cut stone. I have not illustrated the many 105 ways in which these plates 15, 13 and 14 may be formed to give an ornamental contour to the face of the block and an ornamental finish thereto, as this will be obvious 110 to any one skilled in the art.

In the use of my invention the mold is set up to form bricks of the desired size, and then the plastic material is poured into 115 the molds and allowed to set until it is hard when the partitions between the bricks may be removed and the blocks removed from the mold. It is of course to be understood that the inner faces of the mold walls and of the pallets are to be coated with paraffin or oil in order to prevent the plastic material sticking to the walls.

It will be seen that I have provided a 120 mold in which bricks or blocks may be made without tamping or pressing. I further provide a mold which may be used either for forming ordinary bricks, half 125 bricks, or tie bricks, these tie bricks going through both walls and holding the walls 130

together, thus doing away with the use of ordinary steel ties. The half bricks are capable of use on either side of doors and windows, thus avoiding the breaking of 5 bricks and at the same time providing for a face which is uniform without full sized bricks. I further provide a mold which may be used for forming an ornamental contour upon the face of the brick and in 10 which the partition plates having the ornamental configuration thereon may be readily changed as it may be desired.

Having described my invention, what I claim is:

- 15 1. A mold for building blocks comprising a base, a fixed longitudinally extending partition wall, a rail mounted upon the base and extending at right angles to the partition wall, removable side walls mounted on each side of the fixed partition wall and abutting against said rail, the confronting faces of the fixed and movable side walls being formed with vertical grooves, removable partition plates disposable in said 25 grooves, and means for holding the outer

side walls in adjusted position relative to the fixed wall and abutted against said rails.

2. A mold for building blocks comprising a base, a longitudinally extending relatively fixed partition wall, a vertically extending U-shaped strap mounted upon the base at one end of the said wall and forming a socket for the end of said wall, and a socket for the opposite end of the wall attached to the base, U-shaped in plan, whereby the wall may be removed from engagement with said brackets, side walls adjustably mounted upon the base for movement toward or from the fixed wall and extending parallel thereto, and removable partition plates operatively engageable with said fixed and adjustable walls.

In testimony whereof I hereunto affix my signature in the presence of two witnesses.

CECIL L. WATERMAN.
